3,173,461 ADJUSTABLE HACKSAW

Alvin L. Johnson, 70 Piedmont St., Worcester, Mass.
Filed Aug. 3, 1962, Ser. No. 214,736
2 Claims. (Cl. 145—34)

The instant application is a continuation-in-part of abandoned application Serial No. 74,317, filed December 7, 1960.

This invention relates to a new and improved adjustable hacksaw and represents an improvement on the invention disclosed in my Patent No. 2,944,574, issued July 12, 1960.

The principal object of the present invention resides in the provision of a hacksaw frame which is quickly and easily adjustable to take different sizes of saws, say for instance, ten and twelve inch saws, by a very simple manipulation of the frame.

Another object of the invention resides in the provision of new and improved means for locking the ends of the hacksaw blade in the frame, and to this end there is provided an novel mechanism which comprises a cross-slotted member at each end of the frame for reception of the hacksaw blade at said ends, in combination with an annularly movable ring-like member having an interruption therein for receiving the blade, and upon being turned, locks the blade into the slots.

A further object of the invention resides in the provision of the above-described means for locking the blade in the frame at the ends of the blade, said means also providing for angularly adjusting the blade relative to the frame and the handle portion thereof.

Other objects and advantages of the invention will appear hereinafter.

Reference is to be had to the accompanying drawings, in which

FIG. 1 is a view in elevation illustrating the invention;

FIG. 2 is an enlarged section taken longitudinally through the adjusting mechanism for the frame;

FIG. 3 is a view in elevation, partly in section, on an enlarged scale, illustrating one of the blade-holding means;

FIG. 4 is a section taken along the line 4—4 of FIG. 3; and

FIG. 5 is a view in elevation, part in section, illustrating the other blade-holding means.

Reference is made to my above-identified patent for some of the details of construction of the present hacksaw. However, the same comprises any kind of handle which may be desired and convenient such as is indicated by the reference numeral 10. This handle is provided at its upper end with an internal bore or the like 12 for the reception of a fixed tubular member 14 and at the inner end of the bore there is a cross-slot or the like 16 which loosely accommodates a relatively large thumb nut 18.

The tube 14 is fixed in position and slidably and telescopically receives an interior tube 20. Tube 20 may be curved to a right-angular position as at 22 to provide an end at 24 for holding a boss for detachably securing the blade 26 with reference to a like but oppositely positioned boss or member on the handle 10 at 28. This will be hereinafter described.

The tube 20 is provided with a longitudinal slot at 30 terminating in a shoulder 32. Tube 14 has provided thereon by any desired means such as a ring 34, an interiorly extending pin 36 engaged in slot 30. This pin prevents tube 20 from rotating and from being withdrawn out of association with tube 14 and to this end it is provided with an interior boss or stop 38, which together with shoulder 32, provides limiting means for the relative longitudinal adjustment of tube 20 within tube 14.

2

At its inner end, tube 20 is provided with a fixed nut 40, see FIG. 2, and in engagement with this nut there is an interrupted screw 42 fast to the nut 18. When the nut 18 is turned in the appropriate direction, it causes the 5 blade to be tensioned and clamps the tube 20 with reference to the handle.

However, if it is desired to extend tube 20 to take a larger or longer blade 26, then the nut 18 is turned in the opposite direction until the nut 40 is disengaged from the 10 portion 44 of the screw thread, and then the tube may be shifted to engage the portion 46 of the screw-thread with nut 40. Thereupon tension is again applied to the blade 26 which of course may be as much longer than the blade 26 shown in FIG. 1 as the distance between the portions 15 44 and 46 of the interrupted screw.

Screw 42 has a blank 43 that is less in diameter than the screw threads and when tension on the blade has been released the nut is completely free of the screw, either in the blank between threads 44 and 46 or at blank 43. 20 Occasionally, in the absence of blank 43, the nut becomes stuck at the end of the thread 44 by being wedged, but this cannot happen with blank 43 present.

At each end of the frame, i.e., at 24 and 28, there are provided removable bosses which are disclosed in FIGS. 25 2, 3 and 5. These bosses are indicated as to the end of the frame at 24 by reference numeral 48 and this boss comprises a separate, removable cylindrical member which has an annular indentation or groove 50 therein this groove receiving a cross pin 52 holding the boss 48 so 30 it can rotate but cannot shift axially. The boss may be contained in a pair of opposite apertures in the tubing forming the end 24. The member 48 being cylindrical, extends to the right as shown in FIGS. 1 and 3 and terminates in a slit portion, the slit being indicated by the reference numeral 54, see FIG. 4. This slit 54 receives an end of the blade 26 and the split portion has a transverse through aperture therein as indicated at 56 through which extends a ring 58 locking the blade in position.

Ring 58 has an opening 60 by which the blade is admitted into the slit in position shown in FIG. 3. By turning the ring and misaligning the opening 60 with the blade, the blade is held in position when the blade is tightened by means of the thumb-piece 18 as above described.

45 The blade holder at the opposite end of the frame is substantially the same except that the part at 28 has an opening therein which faces the apertures in the end 24 of the tube 20 and in this opening there is a cylindrical member 62 which is substantially the same as 50 that of 48 but reversed. It has an annular groove 64 and it is held in position by a pin 66 so that it can rotate but it is not capable of axial motion. It is also slit at 68 to receive the end of the blade 26 and the slit portions have holes 70 therein for the reception of a ring 55 72 similar to that at 58.

Once the blade is connected at its two ends as above described, it is only necessary to turn the screw in the proper direction in order to impart the necessary degree of desired tension thereto, and this is done in either 60 adjustment of the tubular member 22 as will be clear. Thus the blade is held with the desired tension thereon whatever size of blade is being used. Thus it is seen that the blade itself is angularly adjustable to any position and that when positioned as desired, tension is applied 65 by the wheel 18 turning the screw 42 so that the blade is then firmly held.

Having thus described my invention and the advantages thereof, I do not wish to be limited to the details herein disclosed, otherwise than as set forth in the claims,

70 but what I claim is:

1. A hacksaw comprising a handle, a tubular member in fixed relation thereto and extending therefrom, an

elongated tubular member telescopingly associated with the fixed tubular member and extending outwardly therefrom and from the handle, means on the handle and the telescopic tubular member for engaging and holding a hacksaw blade, and means adjustably securing the telescopic tubular member to said handle and the fixed tubular member in any of a plurality of selected longitudinal positions with respect to the fixed tubular member in order to secure blades of different lengths in the hacksaw,

said second means comprising a nut and a cooperating interrupted screw rod having axially spaced threaded portions selectively engageable in either portion thereof with said nut, with a blank portion between the threaded portions, said nut being fixed to the telescopic tubular member adjacent an end thereof that is located adjacent the handle, the screw rod being engaged with the nut and passing through it, the nut and the screw-threaded portions of the screw rod having full, peripheral mating screw threads,

a rotary actuator fixed to the screw rod and located in the handle for turning the screw rod, the latter being substantially housed and concealed in the telescopic member, the screw-threaded portions on the 25

10

screw rod being longitudinally spaced along the axis of the telescopic tubular member, and the nut being selectively engageable with either screw-threaded portion on said screw rod and being relatively freely

slidable with respect to the rod between the screw-threaded portions.

2. The hacksaw recited in claim 1 including, a blank portion on the screw rod, said blank portion being elongated sufficiently to completely free the screw rod from the nut at one extremity of relative motion of the nut relative to the screw.
